UNITED STATES PATENT OFFICE.

ARTHUR H. FOWLER, OF PHILADELPHIA, PENNSYLVANIA, ASSIGNOR TO THE FOWLER & WOLFE MANUFACTURING COMPANY, OF PENNSYLVANIA.

DESIGN FOR A RADIATOR.

SPECIFICATION forming part of Design No. 28,604, dated May 10, 1898.

Application filed December 15, 1897. Serial No. 662,087. Term of patent 14 years.

To all whom it may concern:

Be it known that I, ARTHUR H. FOWLER, of the city and county of Philadelphia and State of Pennsylvania, have invented a new and original Design for Radiators, of which the following is a specification.

My design for radiators is illustrated in the accompanying drawing, which shows a perspective view of a radiator embodying my design.

The design consists in the shape or conformation of the radiator.

The radiator has the shape of a parallelepiped, composed of a series of layers superimposed on one another and each consisting of a flat section or part having outer tubular portions A A and B B, with cross tubular portions C between the outer portions B B and a series of smaller tubular portions D between each cross-tube C and the tubular end portions A A and the adjacent cross tubular portion C.

The corners of the sections where the outer tubular portions A A and B B are united are formed with heads or enlargements E, which are placed in contact with the corresponding heads at the corners of the adjacent layer or portion, and the edges of these heads are more or less rounded or curved. These heads separate the layers from one another, so as to form spaces between them.

What I claim as new, and desire to secure by Letters Patent, is as follows:

The design for a radiator consisting of the shape or conformation substantially as herein shown and described.

In testimony of which invention I hereunto set my hand.

ARTHUR H. FOWLER.
